UNITED STATES PATENT OFFICE

165,975

STOCKING

Herbert N. Goodman, New York, N. Y., assignor to Triumph Hosiery Mills, Inc., New York, N. Y., a corporation of New York

Application March 25, 1950, Serial No. 8,766

Term of patent 14 years

(Cl. D47—7)

To all whom it may concern:

Be it known that I, Herbert N. Goodman, a citizen of the United States of America, residing at the city, county, and State of New York, have invented a new, original, and ornamental Design for a Stocking, of which the following is a specification, reference being had to the accompanying drawing, forming part thereof.

In the drawing:

Fig. 1 is a side view of a stocking showing my new design; and

Fig. 2 is a rear view thereof with the foot portion dangling.

I claim:

The ornamental design for a stocking, substantially as shown and described.

HERBERT N. GOODMAN.
